RETORT VENTILATING HOOD

Charles W. Hanson, Perth Amboy, N. J., and John Kowalski, Omaha, Nebr., assignors to American Smelting and Refining Company, New York, N. Y., a corporation of New Jersey

Application July 8, 1933, Serial No. 679,492

14 Claims. (Cl. 266—15)

This invention relates to hoods for removing fumes from the vicinity of retort furnaces. The invention is particularly applicable, for example, to retorts for recovering metal values from ores, such as zinc ores, or from metal residues, such as residues from the Parkes process for the desilverization of lead, and provides means to remove the lead, zinc or other fumes which escape during the operation of the retorts in order to prevent contamination of the atmosphere of the plant and to prevent loss of the metal values in such fumes.

The present invention accordingly provides a ventilating hood which cooperates with the retort at all times to prevent escape of such fumes into the air. The hood terminates adjacent the mouth of the retort and is movable so as to follow the mouth of the retort when it is tilted for discharge purposes. The hood is provided with a constricted opening through which air is drawn at high velocity so as to draw the fumes into the hood before they have an opportunity to mix with a large quantity of air.

The invention also consists of certain new and original features of construction and combination of parts hereinafter set forth and claimed.

Although the novel features which are believed to be characteristic of this invention will be particularly pointed out in the claims appended hereto, the invention itself, as to its objects and advantages and the manner in which it can be carried out, may be better understood by referring to certain preferred embodiments thereof which are shown in the accompanying drawing for purposes of illustration only.

In the drawing:

Fig. 1 is a side elevation, partly in section, of a retort and hood constructed in accordance with the present invention;

Fig. 2 is a section taken on the line 2—2 of Fig. 1; and

Fig. 3 is a section taken on the line 3—3 of Fig. 1.

In the various figures like parts have been indicated by like reference characters.

Referring to the drawing more in detail, the invention is shown as applied to a retort 10 which is mounted in a tilting retort furnace 11. The furnace 11 is pivotally mounted, as by a bearing 12, on a stationary frame 13 and is adapted to be tilted into the position shown in dotted lines for purposes of discharge. The retort 10 is provided with a mouth 14 which projects from the front of the furnace 11. The retort and furnace are of any well known construction and only so much

thereof is set forth herein as is necessary to an understanding of the invention. It is to be understood that any standard type of tilting retort furnace may be employed.

For recovering the fumes which are emitted from the mouth 14 of the retort 10 there is provided a fan-shaped hood 15 having a substantially flat side 16 and a convex side 17, terminating respectively in a substantially straight edge 18 and a curved edge 19 which form an elongated opening 23 adapted to be positioned above the mouth 14 of the retort to receive the fumes therefrom. A strengthening rib, such as an angle iron 24, may be secured to the side 16 adjacent the elongated opening 23 and may have a flange 27 adapted to engage the front of the furnace 11 to prevent passage of gases between the hood and the furnace. A similar strengthening rib 25 may be secured to the curved side 17 to hold the same in a proper position. The edge 18 of the hood 15 is supported adjacent the front of the furnace 11 as by a pair of brackets 26 which may be secured to the front of the furnace 11 by any suitable means and which may extend into the opening 23 beneath the strengthening rib 24. Obviously the position of these brackets may be varied as desired and they extend within the mouth of the hood a sufficient distance to support the same when the retort is in tilted position as indicated in dotted lines.

The elongated opening 23 is preferably held a sufficient distance above the mouth 14 so as to provide clearance for the insertion of a condenser or other apparatus (not shown) but sufficiently close thereto to receive the fumes and to prevent the same from being discharged into the air.

The hood 15 is carried by a pipe 30 which is adapted to telescope within a pipe 31 to permit the hood to follow the retort furnace during tilting thereof. A suitable damper 33 may be included within the pipe 30 to permit regulation of the draft. The hood 15 and the adjacent portion 32 of the pipe 30 are tapered from the opening 23 to provide an increasing area for the gases so that the velocity is greatest at the opening 23 and decreases in the direction of flow through the pipe 30. The pipe 31 is pivotally mounted on an exhaust duct 36 which is connected to a suitable source of draft, such as the fan or stack (not shown). The duct 36 is provided with an opening 37 at its lower side which communicates with pipe 31. The pipe 31 carries flanges 38 between which rollers 39 may be mounted in any convenient manner to roll around

the surface of the duct 36 for permitting the necessary pivotal movement of the pipe.

In the operation of the retort a condenser may be connected to the mouth 14 without disturbing the hood 15. The hood will, however, remove any fumes that escape from the mouth 14. A suitable draft is maintained in the duct 36 which draws air and any fumes which may be present into the hood. The constricted opening 23 maintains a high velocity which draws the fumes into the hood before they can mix with the atmosphere.

When the condenser is removed and the retort is tilted for discharge purposes the hood retains its position with respect to the mouth 14 and prevents escape of fumes into the air. It is to be noted that the hood remains at the predetermined spacing from the mouth of the retort at all times. When the retort is tilted, the pipe 31 pivots about the duct 36 and relative sliding movement of the pipes 30 and 31 takes place to permit the hood to follow the mouth of the retort. Preferably, the weight of the pipe 30 and of the hood 15 causes the hood to rest upon the brackets 26 and to follow the movement of the retort. If necessary, however, any suitable means may be utilized for securing the hood to such brackets. Various other means for pivotally connecting the furnace or retort and the hood may, of course, be employed and are embraced by the invention.

The straight edge 18 and the flange 27 remain in engagement with the front of the furnace and prevent escape of fumes between the furnace and the hood. The curved edge 19 forms an opening of sufficient width to receive the fumes but constricted to cause the air to pass therethrough at high velocity. Inasmuch as this opening is located adjacent the mouth 14 of the retort 10, the fumes from the retort are drawn into the hood before they have an opportunity to mix with any substantial quantity of air. Hence, the fumes are in a comparatively concentrated form and may be readily applied to a metal recovery apparatus if desired. Furthermore, by increasing the air velocity at a point adjacent the retort mouth and thereby reducing the quantity of air which must be moved through the duct, the power requirements are reduced to a minimum.

Although a preferred embodiment of the invention has been shown for purposes of illustration, it is to be understood that various changes and modifications may be made by a person skilled in the art, and that the invention is only to be limited in accordance with the following claims when interpreted in view of the prior art.

What is claimed is:

1. In combination, a retort furnace having a retort therein, means supporting said furnace for tilting movement, a ventilating hood, a stationary exhaust duct, means attached to the furnace for pivotally supporting the hood for movement with said furnace in a position to receive fumes from the mouth of the retort and means interconnecting said hood and said duct while permitting the above movement of said hood.

2. In combination, a retort furnace having a retort therein, means supporting said furnace for tilting movement, a ventilating hood having an opening adjacent and above the mouth of said retort adapted to receive fumes therefrom and having means engaging the front of said furnace to prevent passage of fumes between the hood and furnace and means attached to the furnace for pivotally supporting said hood for movement

with said furnace whereby the same relative position of said opening to the mouth of said retort is maintained when the furnace is tilted.

3. In combination, a retort furnace having a retort therein, means supporting said furnace for tilting movement, a ventilating hood having an opening adjacent and above the mouth of said retort adapted to receive fumes therefrom and having means engaging the front of said furnace to prevent passage of fumes between the hood and furnace and means for pivotally supporting said hood on said furnace for movement therewith whereby the same relative position of said opening to the mouth of said retort is maintained when the furnace is tilted.

4. In combination, a retort furnace having a retort therein, a ventilating hood having an opening, means attached to the furnace for pivotally supporting the hood with said opening above and adjacent the mouth of said retort and means to cause a high velocity air current to pass over the mouth of said retort and through said opening to thereby draw in fumes emitted from said retort.

5. In combination, a tiltable retort having a mouth, a hood having a constricted opening, and means attached to the retort for pivotally supporting the hood to move with said retort while maintaining said opening spaced from said mouth to receive fumes therefrom.

6. In combination, a tiltable retort having a mouth, a hood adapted to cooperate with the mouth means attached to the retort for pivotally supporting the hood adjacent said mouth and a telescoping pipe connected with said hood and extending upwardly therefrom to permit vertical movement of said hood when said retort is tilted.

7. In combination, a tiltable retort having a mouth, a hood having a constricted opening, means attached to the retort for pivotally supporting the hood with said opening adjacent said mouth in a position to receive the fumes emitted therefrom, an exhaust duct, and means connecting said hood to said exhaust duct, said last means being adapted to permit said hood to follow the tilting movement of said retort.

8. In combination, a tilting furnace, a retort therein, a ventilating system therefor comprising an exhaust duct, a telescoping pipe associated therewith, a fan-shaped hood associated with said pipe, said hood having a flat side and a curved side terminating respectively in a straight edge and a curved edge, said edges being spaced to provide an elongated opening therebetween, means engaging said straight edge to hold the same adjacent said furnace above the mouth of said retort, and means to permit movement of said pipe for maintaining said hood in said predetermined position relative to said retort when said retort is tilted.

9. In combination, a furnace from which fumes are emitted, a ventilating hood having a constricted opening adapted to receive said fumes, said opening having less cross-sectional area than said hood whereby a high velocity air current is caused to pass therethrough for drawing the fumes into said hood and means attached to the furnace for pivotally supporting the hood thereon.

10. A retort ventilating system for a retort furnace comprising an exhaust duct, a pipe pivotally mounted thereon, a hood carried by said pipe, said hood having a constricted opening through which gases are adapted to pass at high velocity and means attached to the furnace for pivotally supporting the hood thereon.

11. A ventilating system for a tilting retort furnace comprising an exhaust duct, a hood having a constricted opening adapted to receive fumes discharged from said furnace, means interconnecting said duct and said hood, said means being adapted to permit said hood to swing outwardly and downwardly to follow the tilting movement of said furnace and means attached to the furnace for pivotally supporting the hood thereon.
12. In combination, a furnace from which fumes are emitted and a ventilating means comprising a pipe terminating in a hood and tapered in cross section toward said hood, said hood having a constricted opening adapted to receive said fumes, said tapered pipe and constricted opening causing an air current of high velocity to pass into said hood for drawing said fumes away from said furnace and means attached to the furnace for pivotally supporting the hood thereon.
13. In combination, a retort furnace, a hood having an elongated opening above the mouth of

the retort and a flange mounted on said hood adjacent said elongated opening, said flange being adapted to engage the front of said furnace to prevent passage of gases therebetween an exhaust duct communicating with said hood, said duct and said hood having a greater cross-sectional area than said opening whereby air is caused to pass into said opening at high velocity.

14. In combination, a tilting furnace, a retort therein, a ventilating system therefor comprising an exhaust duct, a telescoping pipe associated therewith, a fan-shaped hood associated with said pipe, said hood being formed with an elongated opening, means for pivotally supporting the hood on the furnace with said opening above and adjacent the mouth of the retort and means to permit movement of said pipe for maintaining the hood in a predetermined position relative to said retort when the retort is tilted.
